FISHING TOOL

Kenneth C. Hawkins, Arcadia, Calif.

Application March 13, 1950, Serial No. 149,260

3 Claims. (Cl. 294--65.5)

1

The application relates to fishing tools particularly adapted to retrieving magnetizable objects from well casings and to tools which are found particularly advantageous in deep well casings of the type used extensively in sinking oil wells.

In oil well drilling where it is the practice to sink oil wells into the earth accompanied by steel casings to distances of thousands of feet drilling operations become particularly expensive. Although tools have been contrived which may eventually bring objects in the well to the surface, excessive time consumed in such operations interferes with or interrupts the drilling before the desired depth is reached and causes objectionable and sometimes prohibitive loss of time frequently jeopardizing the economic success of the operation. Therefore when objects such as wrenches, drill bits, sections of pipe and the like inadvertently fall into the casing the time and effort required to retrieve them is a substantial factor in drilling operations. Moreover, the deeper the well, the more time is lost especially when objects, partly retrieved, are lost or dropped a second time making necessary new efforts to lift them.

Heretofore a great variety of fishing tools have been devised utilizing one mechanical expedient or another for grappling objects which have fallen into the well with a sufficiently tight grip so that they may be hauled upwardly out of the casing throughout distances of some thousands of feet. Naturally the greater the depth of the well the longer is the time needed to lower and raise the fishing tool. Unless the grip of the tool on the object to be retrieved is sufficiently secure, the hold on the object may be dislodged one or many times before the object is finally pulled out of the casing at the surface. The cost of the fishing operation is therefore increased a considerable extent whenever the object is not successfully retrieved during the first fishing operation.

Inasmuch as almost all objects which are likely to fall into a drilled well are of a ferrous and therefore magnetic nature, the use of a magnet for retrieving the objects has suggested itself in the past. The character of a well is, however, such that using a magnet has heretofore presented such difficulties that successful utilization of magnets for this purpose has been defeated. The fact that the well casing is of a magnetic material short circuits the magnetic field, thereby reducing its strength to an unworkable quantity when the magnet and sometimes the object it-

2

self strikes against the interior of the casing. When the object is of irregular shape the grip of the magnet may be dislodged by reason of the object bumping against the well casing on the way up even though the strength of the magnet is not materially reduced. Some objects which need to be retrieved are so heavy that the strength of the magnet cannot be depended upon to continue to attract the object with sufficient force throughout the entire lift from the bottom of the well to the surface.

It is therefore among the objects of the invention to provide a new and improved magnetic fishing tool for well casings which is adapted to retrieve metallic objects of any and all sizes which are ordinarily dropped into the well.

Another object of the invention is to provide a new and improved magnetic fishing tool which utilizes an auxiliary retainer or grappling device to provide an independent grasp upon the object to be retrieved while it is being lifted to the surface of the well.

Still another object of the invention is to provide a new and improved metallic fishing tool which is so constructed that the magnet is shielded from contact with the casing so as to maintain sufficient effectiveness in the force of the magnet throughout the entire lift from the bottom of the well to the surface.

Still another object of the invention is to provide a new and improved magnetic fishing tool for wells by which an auxiliary retainer or grappling device can be released when the object to be retrieved is drawn to the magnet so that the retainer forms either a support upon which the object may be rested while drawn to the surface or which, for objects of considerable length, may be moved so as to grip the exterior of the object in a way such that no matter how great the pull may be upon the object the grip will be held until the object is lifted clear of the well.

Still further among the objects of the invention is to provide a new and improved magnetic fishing tool for wells wherein a magnet is movably retained in a casing in a manner such that it can be extended to a position most advantageous for initially engaging an object to be retrieved and thereafter withdrawn together with the object to a position in the casing wherein the object if need be may be grasped by some auxiliary mechanism, thereby adding to the grip upon the object while the fishing tool is being withdrawn together with the object from the well.

With these and other objects in view, the in-

vention consists in the construction, arrangement and combination of the various parts of the device whereby the objects contemplated are attained, as hereinafter set forth, pointed out in the appended claims and illustrated in the accompanying drawings.

In the drawings:

Figure 1 is a longitudinal sectional view of the magnetic fishing tool with the parts in initial position shown being lowered into a well casing.

Figure 2 is a longitudinal sectional view of the fishing tool showing its operation in grasping an object to be retrieved which has a length greater than the length which could be accommodated within the fishing tool.

Figure 3 is a longitudinal sectional view of the fishing tool shown in engagement with a relatively small object for lifting the object from a well.

Figure 4 is a cross-sectional view taken on the line 4—4 of Figure 1.

Figure 5 is a fragmentary longitudinal sectional view showing one form of grappling means in an initially withdrawn position as for lowering into the well.

Figure 6 is a longitudinal sectional view of a modified form of the device showing a permanent magnet.

Figure 7 is a cross-sectional view taken on the line 7—7 of Figure 6.

When using magnetic force to recover, retrieve and withdraw a magnetizable object from a deep well special precautions need be taken to assure a sufficient grip upon the device no matter what its shape while it is being attracted to the area within which a proper grip may be secured upon it and also during the entire lift of the device from the bottom of the well to the surface. In the magnetic fishing tool of the present invention the tool includes a container for the magnet which opens downwardly in such a manner that when the objects to be retrieved are within the field of attraction of the magnet they may be drawn to a position with respect to the fishing tool so that a firm grasp upon the objects may be assured at all times regardless of the size or shape of the object or the character of the interior of the well casing in which the fishing tool is used.

As shown in the drawings there is depicted a section of steel well casing 10 which may be assumed to be at any depth which might ordinarily be reached by conventional well drilling methods. A magnetic fishing tool indicated generally by the reference character 11 is shown being lowered into the casing 10 by means of a cable 12 secured to the tool by a cable connection 13.

The fishing tool comprises in the example chosen a cylindrical container 14 of somewhat elongated character which has its upper end closed by a cover 15 and which has a lower open end 16. The container should preferably be of a non-magnetic material such as copper or aluminum so as to form an effective shield to prevent anything within the container having a magnetic contact with the steel of the casing 10.

Within the casing is a piston 17 having a sliding packing 18 so that the piston forms a closed chamber 19 within the container. A fitting 20 mounted in a cover 15 provides access to the chamber 19 through a flexible hose line 21 which connects to a shut-off valve 22 located above and outside of the casing 10. By this means the chamber 19 may be filled with a suitable fluid under pressure if desired and by means of which

the contents of the chamber may be exhausted.

Mounted upon and below the piston 17 is a coil 23 of an electro-magnet supplied by one wire 24 to one terminal 25 of the electro-magnet. The other terminal may be grounded if desired through the cable 12. The wire 24 may be helical or in any event extendible by some conventional means and permanently secured to a binding post 26. From the binding post a wire 27 may extend upwardly through the casing to a suitable source of electric power.

To complete the electro-magnet there is shown a stationary core 28 of magnetizable material, a cylindrical portion 29 of which forms a center 15 for the coil 23 and a lower portion 30 of which forms a flat face for the magnet. The core is shown threadedly engaged at 31 with the piston so that the piston and the magnet act as a single unit.

For proper protection of the winding of the magnet there may be provided a non-magnetic wrapping 32 entirely surrounding the coil and the outer circumference of the portion of the core extending below the coil. It will be appreciated that fishing tools of this kind when extended deep into wells are apt on occasions to be entirely submerged in mud and water so that proper protection for the magnet is advisable. There must, however, be a sufficient clearance between the magnet and the inner wall of the chamber 19 so that the magnet and piston unit can raise and lower with perfect ease.

At the lower end of the container 14 there may be provided a shoulder 35 upon which a complementary shoulder 36 on the magnetic core is adapted to rest, thereby permitting a lower face 37 of the magnetic core to extend outwardly substantially flush with the outside open end of the container 14.

In Figure 1 the electro-magnet is shown in its lowermost or extended position which is the position it would have while being lowered into the well.

Figures 2 and 3 show the electro-magnet and piston unit in withdrawn position removed from the open end of the container. This is the position the electro-magnet piston unit will assume after the object has been attracted to it and the electro-magnet withdrawn to the position it will occupy while the fishing tool is lifted from the well.

At the lower end of the container there is provided a retaining means which in the selected embodiment is shown as comprising oppositely disposed arms 40 and 41, 42 and 43. As shown in greater detail in Figure 5 with respect to the arm 40 the container is provided with a recess 44 adapted to receive the arm in a position sufficiently withdrawn so that the electro-magnet piston unit is free to slide downwardly to lowermost position. The arm is shown pivoted by means of a pin 45 to the lower end of the container and the stored energy of a spring 46 located behind the arm may be utilized to force the arm outwardly after the electro-magnet piston unit has been lifted to a withdrawn position in the container 10. The arm may also be provided with a serrated or roughened section 47 adapted for use on special occasions in grasping the object which is to be removed.

In operation fluid is pumped into the chamber 19 through the shut-off valve 22 and hose line 21 so as to force the piston to lowermost position. This is the position shown in Fig. 1. With the piston in this position the shut off

valve is closed and the container lowered by means of the cable 12 into the well casing. The core of the electro-magnet will be at its outermost position substantially flush with the lower end of the casing during this operation.

When the fishing tool reaches the bottom of the well the magnetizable object to be retrieved will be drawn to and attach itself by magnetic force to the exposed core of the electromagnet. During this phase of the operation the electro-magnet may be supplied with current through the wire 24.

After the attraction has been accomplished the piston together with the electro-magnet is withdrawn into the container to a position removed from the lower open end. These are the positions shown in Figures 2 and 3. This is accomplished by opening the shut-off valve 22 permitting the fluid in the chamber 19 to be discharged. The shut-off valve 22 is then closed again and the tool is lifted to the surface. As the piston is raised, the wire 24 coils upon itself to the position shown in either Figure 2 or 3.

Movement of the electro-magnet together with the piston as thus shown serves, in Figure 2, to draw a section of pipe 48 upwardly and into the lower end of the container. Where as in this example the section of pipe is too long to be entirely withdrawn into the container, the section of pipe is grasped by the arms 40 and 41, 42 and 43. The grasp of the arms becomes effective as the electro-magnet is lifted upwardly clear of the arms in the positions illustrated in Figure 5. After the electro-magnet has cleared, springs 46 will force the arms inwardly so that opposite arms are urged toward each other and into contact with the exterior surface of the object which in this case is the section of pipe 48. Upon engagement the serrated portions of the arms grip the exterior surface of the section of pipe and the weight of the pipe will cause the section of pipe to jam between opposite arms and thus provide a satisfactory grip for the arms upon the section of pipe. The section of pipe thus secured is withdrawn to the surface by lifting upon the cable 12. Thus engaged it will not matter that the section of pipe touches the interior of the steel casing since because of the auxiliary grip of the arms there will be no short circuiting of the magnetic field such that it will cause the section of pipe to be released. In fact the electric coil may be deenergized once the section of pipe has been grasped and mechanical means depended upon solely for holding the section of pipe while it is being lifted to the surface.

In the example illustrated in Figure 3 the object to be retrieved may be an object such as a large nut 50 still small enough to enter completely within the lower end of the container 10. In this example after the nut has attached itself to the core of the electro-magnet and has been drawn inwardly into the casing, as the electro-magnet and piston rise to the withdrawn position, the arms 40 and 41, 42 and 43 will drop forming a temporary false bottom for the container. The width of the arms is somewhat arbitrary and may be proportioned as desired so that the arms when lowered to the position shown in Figure 3 may cover substantially all or only a part of the open end of the container 14. The electro-magnet will of course remain energized until the nut is lifted clear of the arms. In their initial position as illustrated in

Figure 5 the springs 41 will push the arms inwardly to a point from which they will then drop by gravity to the positions shown in Figure 3. In the lowermost position there illustrated the arms may be retained upon the shoulder 35 which initially served to bottom the electro-magnet. Once the arms are dropped to the position shown in Figure 3 the electro-magnet may be de-energized and the object will be securely held by the arms until it is lifted to the surface.

In the modified form of the device shown in Figures 6 and 7 there is illustrated a permanent magnet 60, here shown as a double-pole magnet, having two north poles 61 and 62 and two south poles 63 and 64. Where a grip of lesser strength is satisfactory a single-pole magnet may suffice. In the particular example chosen for illustration the north and south pole pieces are retained against a magnetic disk 65 forming a piston by means of a bolt 66 and a washer 67. The disk 65 may be provided with a packing ring 68, thereby serving as a piston adapted for reciprocation sliding along the inner wall 69 of the casing 14. Movement of the piston 65 is accomplished by the same fluid agency as described in connection with Figure 1.

In using a permanent magnet the object to be retrieved will at all times be drawn toward the permanently magnetized poles. Although the magnet will at all times be shielded from contact with the interior of the casing 10 by the interposition of the non-metallic jacket or container 14, it is conceivable that the object to be retrieved might be so long that it protrudes outwardly below the container and also that it might be of such character that it could not be firmly gripped by the arms 40 and 41, 42 and 43. Under these circumstances the forces of the magnet entirely would have to be relied upon to hold the object in attracted position to the fishing tool until the tool could be lifted clear of the well casing. Because the object to be retrieved is of a magnetizable character is therefore becomes particularly important that the magnet be shielded or guarded from direct contact with the wall of the casing which otherwise would tend to short circuit the magnetic field and diminish the magnetic force to a point where it would be likely to lose its grip upon the object being retrieved. Clearly too in the last example for objects small enough to be entirely withdrawn into the casing by action of the permanent magnet, both the magnet and the objects are positively shielded from contact with the walls of the casing so that even if the operation of arms 40, 41, 42 and 43 were defective or jammed the magnetic force would continue undiminished by any short circuit to the end that the object could be lifted throughout the full distance from the bottom of the well without becoming dislodged.

On some occasions where the object to be retrieved might not be of any substantially great weight the magnet need not be extended to its lowermost position but lowered in withdrawn position in which position it could be sunk to a point where the object would be within the field of the magnet and the object thereby drawn into the open end of the container into contact with the magnet and even past the arms without it being necessary to manipulate the magnet within the container.

Once the fishing tool accompanied by the retrieved object has been lifted clear of the well the arms can be pressed back sufficient to release the

object from the tool. Releasing of the object may be facilitated by laying the fishing tool on its side or on some occasions turning it upside down so as to make easier the operation of releasing the arms. In the case of small objects held by the permanent magnet release may be more readily accomplished by forcing the fluid into the chamber 19, thereby shifting the magnet to extended position in which position the retained object can be more readily dislodged.

Accordingly there has been provided a mechanism making the use of magnets in retrieving objects from deep wells especially advantageous and successful which is clearly adapted to operate with great assurance regardless of the size or shape of any magnetizable object which could fall into a well. It will be appreciated of course that in view of the fact that the diameters of well casings vary to some extent, fishing tools would be made small or large depending upon the size of the casing worked without, however, in any way altering the principle of operation of the device.

While I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent devices.

Having described my invention, what I claim as new and desire to secure by Letters Patent is:

1. A fishing tool for retrieving magnetizable objects from well casings comprising a hollow container, a magnetic piston unit slidably fitting within said container forming a closed chamber therein, said magnetic piston unit having a withdrawn position within the container and an extended object-engaging position at the lower end of the container, a fluid connection from the chamber to the surface and a shut-off valve on the connection, a fluid in said chamber adapted to be admitted thereto through said connection, said fluid being operable upon opening of said shut-off valve when the container is in the well to effect movement of said magnetic piston unit to withdrawn position, retaining means on the container for said magnetizable objects, said retainer having an object-engaging position and means adapted automatically to move said retainer to said object-engaging position.

2. A fishing tool for retrieving magnetizable objects from well casings comprising a hollow cylindrical container of non-magnetic material, a piston including a magnet slidably fitting within said container forming a closed chamber therein, said piston and magnet having a withdrawn position within the container and an extended object-engaging position at the lower end of the container, a fluid connection from the chamber to the surface and a shut-off valve on the connection, a

fluid in said chamber adapted to be admitted thereto through said connection, a non-magnetic cover for said magnet, a retaining means movably attached to the container at the open end thereof adapted to engage said objects, said retainer having a normally inoperative position and having an operative position adapted to engage the exterior of an object to be retrieved, and means adapted automatically to move said retainer to object-engaging position.

3. A fishing tool for retrieving magnetizable objects from well casings comprising a hollow cylindrical container of non-magnetic material, a piston slidably fitting within said container forming a normally closed chamber therein, said piston having a withdrawn position wherein the volume of the chamber is diminished and an extended position wherein the volume of said chamber is expanded, a shut-off valve outside the casing, a fluid connection from the chamber to the shut-off valve, a fluid in said chamber adapted to be admitted thereto under pressure through said connection, said fluid being operable upon opening of said shut-off valve to effect a movement of the piston to the withdrawn position, an electro-magnet on said piston having a core extending to the lower face of the magnet and an operating device outside the casing connected thereto, a non-magnetic cover for said electromagnet, mutually opposed retainers for said objects having pivotal connections to the container near the open end thereof and oppositely disposed roughened surfaces thereon, a stop shoulder on the container at said open end cooperable alternately with the plunger in extended position and with the retainers when extended during said withdrawn position of the piston, said retainers having lowered positions engaging the shoulder forming a bottom for the container in one object-engaging position and partially lowered positions in another object-engaging position wherein the roughened faces are in mutually opposed relationship adapted to grasp the exterior of an object to be retrieved, and automatically extending means for said retainers adapted automatically to move said retainers to said object-engaging positions.
